UNITED STATES PATENT OFFICE.

P. STRODE BROWN, OF GUTHRIESVILLE, PENNSYLVANIA.

MIDDLENS-PURIFIER.

SPECIFICATION forming part of Letters Patent No. 254,604, dated March 7, 1882.

Application filed January 23, 1882. (No model.)

To all whom it may concern:

Be it known that I, P. STRODE BROWN, a citizen of the United States, residing at Guthriesville, in the county of Chester and State of Pennsylvania, have invented certain new and useful Improvements in Middlens-Purifiers; and I do hereby declare that the following is a full, clear, and exact description of the same, reference being had to the annexed drawings, making a part of this specification, and to the letters and figures of reference marked thereon.

Figure 1 is a side elevation of a machine embodying my invention. Fig. 2 is a longitudinal section thereof. Fig. 3 is a view of that end of the machine to which is connected the suction-fans, and Fig. 4 is a view of the opposite end of the machine.

The present invention has relation to a novel construction of a middlens-purifier, as will be hereinafter described, and subsequently pointed out in the claims.

In the accompanying drawings, A represents the chest containing the usual reel, B, covered with bolting-cloth, and at the end of 25 said chest is located the air-conductor C, communicating with the air-conveyer D, said conveyer at its opposite end communicating with a suitable suction-fan, E. A slide near top of conductor C, as shown at a, regulates the draft 30 through conductor and conveyer D, and a suitable door, b, is provided to obtain access to the interior of the air-conductor when found necessary.

The top of the air-conductor C is provided 35 with a feed-spout consisting of three tubular sections, c d e, the section e being stationary or rigidly secured to the top f of the conductor, while the section d is suspended therefrom so that it will swing laterally in any direction to 40 admit of the lower section, e, being adjusted in a horizontal direction to insure that the middlens as it passes down the feed-spout will strike the center or apex of the conical spreader F. This horizontal adjustment of the lower section, e, is made by the set-screws g passing 45 through a ring, h, connected to the interior of the conductor C, said section e passing down through the ring, and the ends of the set-screws bearing against the same. The sections 50 c d e are of different diameters, so that they

will fit one in another and enable the feed-spout to be shortened or lengthened to regulate the feeding of the middlens to the machine. The conical spreader F is also adjustable vertically, and held at the desired height by set-screw i 55 to regulate the spreading of the middlens.

The suction-fan E produces an upward current of air through the conductor C, as indicated by arrows, which takes with it the impurities from the middlens as they are thrown off from the spreader F and carries them through conveyer D out through mouth of the fan. The middlens as they leave the spreader F are collected by hopper G and taken by conveyer H to the reel B. A suction-fan, I, 65 draws the air through the middlens in the reel B and through the chest A around the exterior of the reel, the air being drawn through openings k l. The openings k l are formed in the end of the chest A, and are regulated by 70 slides m, and the impurities as they are taken or withdrawn from the middlens in the reel and chest pass over partition n and out through the fan I. The suction-fans E I are provided with suitable slides, K, operated by rods o, one 75 end thereof connected to the slides and the opposite end working in brackets p. The slides K are formed with slots q, so as to straddle the shaft r of the fans to enable the slides to be closed, or partially closed, over the openings 80 communicating with the sides thereof. A set-screw, s, holds the rods o in the position placed, and also the slides K. The middlens as they pass from the reel B into hopper L are received by the rotary conveyer M and conveyed in the 85 direction indicated by the arrows, Fig. 2, to the discharge-spout t.

Below the conveyer M is a partition, N, having a series of openings, u, each of which is closed by a slide, v. Any of these slides may 90 be drawn to admit of the middlens passing through the openings u to the conveyer P, which conveys the middlens in the opposite direction to the conveyer M, as indicated by arrows.

The spout w under the conveyer P is for the purpose of taking off middlens to return to feed-spout at the head of the machine, if so desired; and the hopper R is for the purpose of carrying off tailings from the machine.

The suction-fans I E are arranged upon the same shaft, and each performs its separate function of creating a current of air through the different parts of the machine to carry 5 with it the impurities from the middlings, as hereinbefore described.

The chest A has doors S T, suitably connected to each side thereof, said doors having glass panels or windows y.

10 The slotted slides K are arranged to operate in extensions W, connected to the side of the suction-fans.

The machine and the several operating parts may be driven by the common belts, pulleys, 15 and gearing usually employed in this class of machines, and therefore a detailed description of this part of the machine is considered unnecessary.

10 The several parts of the machine are supported upon a suitable frame-work, Y.

Having now fully described my invention, what I claim as new, and desire to secure by Letters Patent, is—

1. The combination of fans E I, slides K, reel B, air-conductor C, and the chest A, having 25 openings k l and slides m, substantially as and for the purpose set forth.

2. The adjustable feed-spout consisting of the sections c d e, constructed as described, in combination with the conical spreader F, 30 adapted to be adjusted vertically, as and for the purpose specified.

In testimony that I claim the above I have hereunto subscribed my name in the presence of two witnesses.

P. STRODE BROWN.
